UNITED STATES PATENT OFFICE.

JOHN BRINSMEAD, OF LONDON, ENGLAND, ASSIGNOR TO JOHN BRINSMEAD & SONS LIMITED, OF LONDON, ENGLAND.

COMBINED PIANOFORTE AND AUTOMATICALLY-ACTUATED MECHANISM THEREFOR.

No. 868,406.

Specification of Letters Patent.

Patented Oct. 15, 1907.

Application filed April 9, 1906. Serial No. 310,695.

To all whom it may concern:

Be it known that I, JOHN BRINSMEAD, a subject of the King of Great Britain, and resident of The Brinsmead Works, Grafton Road, Kentish town, London, England, 5 director of John Brinsmead & Sons Limited, pianoforte manufacturers, have invented certain new and useful Improvements in or Connected with Combined Pianofortes and Automatically-Actuated Mechanism Therefor, of which the following is a specification.

10 This invention relates to pianofortes which are adapted to be played either manually (*i. e.* in the ordinary way) or mechanically by means of automatically actuated mechanism which leaves the keyboard entirely exposed to view, and the invention has for its principal

15 object to enable the automatic mechanism to operate upon the hammer action without the movement being transmitted either through or to the keys or key levers, so that the latter are undisturbed when the instrument is being mechanically played, and the consequently 20 useless wear and tear of the key levers and associated parts is avoided.

A further object of the invention is to render such instruments capable of being played both manually and mechanically at one and the same time if desired, so 25 that (say) the *secondo* and *primo* parts of a duet may be performed by the automatic mechanism and by hand respectively, or vice versa. The invention is thus designed to give to pianofortes provided with automatic playing mechanism of the kind referred to, a 30 greatly extended range of usefulness and artistic capacity, by affording at will, opportunities not only for practice in the case of duets and other concerted pieces, but for individual characterization of selected portions of a composition and also for (say) improvisation upon 35 a ground base, or again, for suppression of any part of the harmony which is to be brought out by some other instrument such as the violin or by the voice. As a further result of the invention, there is a diminution of 40 the effort required to actuate the hammers by means of the automatic mechanism.

According to the present invention means are provided whereby, in the case of each note-producing element throughout the entire scale of the instrument, the finger-key appertaining to that element, and the corresponding mechanically operated push or equivalent member of the automatic playing mechanism, are enabled to act independently of one another upon the sticker or prolonge whereby movement is communicated to the hammer action, so that neither is the automatic mechanism affected by manual operation of the key, nor is the key depressed by the movement of the automatically actuated push.

For the sake of convenience, the invention will be described with special reference to pneumatically oper-

ated or controlled automatic playing mechanism in- 55 closed within the pianoforte, it being understood however that the automatic mechanism might be otherwise operated or controlled, as for example electro-mechanically.

In the accompanying drawings Figure 1 is a part vertical section from front to rear of a pianoforte of the kind referred to, showing so much of the mechanism of a single note-producing element as is necessary to illustrate the application thereto of the invention, all the parts being in position of rest. Figs. 2 and 3 are similar views, 60 65 the ordinary finger-key mechanism and the automatic playing mechanism being respectively shown as in operation.

In the drawings A is the rear portion of the finger-key lever appertaining to the note-producing element 70 illustrated; B is the corresponding sticker or prolonge whereby movement is transmitted from the key lever A to the hammer action (which latter may be of any convenient or preferred type of construction); and C is the push or piston rod appertaining to the correspond- 75 ing element of the pneumatically actuated automatic playing mechanism. D is the usual key-bottom. The prolonge B works as usual in an approximately vertical direction, the upper end of its stem being preferably guided by means of a radius link E pivoted as at e to 80 the prolonge and as at f to a fixed member F of the frame of the instrument. The lower end b of the prolonge, which for this purpose may be of inverted T-shape as indicated, is provided with separate and independently adjustable buttons G, H (tipped with felt in 85 the usual manner) whereby to enable the prolonge to be actuated by the corresponding finger key and pneumatic push respectively, said buttons being arranged the one directly behind the other and carried by stems g, h threaded to screw through corresponding holes in 90 the T-end b of the prolonge. That button G which is actuated by the key is towards the front, and may rest upon a rearward prolongation j of a lead block J fixed to the underside of the rear end of the key lever A, said block being adapted to serve in place of the usual counterpoise for the key, and being fitted to rest normally upon the key-bottom D through the medium of a felt cushion d. The other or rear button H rests upon a block K constituting the head of the pneumatic piston rod or push C, which works vertically through guides 100 provided in or carried by the key-bottom D upon which the block K may normally rest as indicated in Figs. 1 and 2.

The block K is provided at its upper end with a vertical hole k which serves as a guide for the lower end 105 of the prolonge B, the stem of the screw stem h (whereby the corresponding button H is adjustably attached beneath the lower end of the prolonge) being down-

wardly lengthened as at *l* to an extent greater than the amount of the vertical movement of the prolonge, and made plain (*i. e.* devoid of screw threads) so as to be adapted to work without friction in the hole *k* in the 5 block *K*. When on the one hand the prolonge *B* is raised by the actuation of the key-lever *A* (as shown in Fig. 2) the stem *l* slides upward through, but does not leave, the hole *k*, and when on the other hand the prolonge is raised by the actuation of the pneumatic piston 10 rod *C* (as shown in Fig. 3) the stem *l* of course remains in the hole *k*, which thus always serves as a guide for the lower end of the prolonge and renders further guidance thereof at this point unnecessary.

As will be seen from the drawings, the result of the 15 construction described is that the actuation of the pneumatic piston rod or push *C* leaves the key-lever *A* unaffected, and vice-versa, so that when the automatic playing mechanism is in use, the keys of the pianoforte remain at rest, and when the instrument is played 20 manually, no resistance or impediment is offered by the automatic mechanism to the movement of the hand. Hence also, both the manually and the automatically 25 operated mechanisms may be used at the same time without either of them suffering hindrance or obstruction of any kind from the other.

The key-bottom *D* of a pianoforte being of considerable thickness, the pneumatic piston rods or pushes *C* which extend vertically upwards from the pneumatic chest through the key-bottom are preferably made to 30 pass through clearing holes in the latter, and may be guided only at the upper and lower faces of the key-bottom as shown. For this purpose the guides are constituted by holes in a pair of longitudinally extending bars *m*, *n*, the piston rods or pushes *C* being made an 35 accurate working fit in the holes. In order to insure perfect registration of the respective holes in the one bar *m* or *n* with those in the other, the bars are formed by dividing at a horizontal plane a single rail after the same has had the entire series of holes drilled vertically 40 through it, the two half-thicknesses *m* and *n* thus formed being, after separation, fixed securely in position by being let into corresponding parallel grooves

provided the one at the upper and the other at the lower face of the key-bottom as indicated.

1. In a manually and mechanically operated pianoforte 45 the combination of prolonges, front and rear adjustable buttons attached to the lower ends of the prolonges, key levers, extensions on the key-levers carrying the front buttons, mechanically operated mechanism, piston rods connected to the mechanism and vertically movable blocks 50 carrying the rear buttons and connected to the piston rods, substantially as specified.

2. In a manually and mechanically operated pianoforte 55 the combination of key-levers, extensions on the rear of the key-levers, a prolonge for each of the key-levers, radius arms attached to the upper end of the prolonges, front and rear adjustable buttons attached to the lower end of each of the prolonges, mechanically operated mechanism, piston rods connected to the mechanism and vertically movable blocks connected with the piston rods, the front 60 and rear buttons respectively bearing on the extensions of the key levers and vertically movable blocks, substantially as specified.

3. In a manually and mechanically operated pianoforte 65 the combination of key levers, extensions on the rear of the key-levers, prolonges, radius arms pivoted to the upper end of the prolonges, front and rear buttons, screws for adjustably connecting the buttons to the lower end of the prolonges, mechanically operated mechanism, piston rods connected to the mechanism and vertically movable 70 blocks connected to the piston rods, the front and rear buttons respectively being adjustable relatively to and bearing on the extensions of the key-levers and vertically movable blocks, substantially as specified.

4. In a manually and mechanically operated pianoforte 75 the combination of key levers, extensions on the rear of the key-levers, prolonges, radius arms pivotally attached to the frame of the pianoforte and the upper ends of the prolonges, front and rear adjustable buttons attached to the enlarged lower ends of the prolonges, mechanically 80 operated mechanism, piston rods connected to the mechanism, vertically movable blocks connected to the piston rods, each block being provided with a vertical guide hole, and stems projecting from the rear buttons and extending into the holes of the blocks to maintain in conjunction with the 85 radius arms, the position of the buttons relatively to the key levers and the mechanically operated mechanism, substantially as specified.

JOHN BRINSMEAD.
